ATTORNEYS.

UNITED STATES PATENT OFFICE.

HUGH DICK, OF THREE-MILE BAY, NEW YORK.

IMPROVEMENT IN THILL-COUPINGS.

Specification forming part of Letters Patent No. 178,122, dated May 30, 1876; application filed April 1, 1876.

To all whom it may concern:

Be it known that I, HUGH DICK, of Three-Mile Bay, in the county of Jefferson and State of New York, have invented a new and valuable Improvement in Thill-Coupling; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal vertical section of my thill-coupling, and Figs. 2, 3, and 4 are perspective detail views of the same. Fig. 5 is a front elevation thereof.

The nature of my invention consists in the construction and arrangement of a thill-coupling, as will be hereinafter more fully set forth.

In the annexed drawing, A represents the bottom plate or bar of an ordinary wagon-clip, which plate goes under the axle-tree. At the front end of the plate A is formed the shackle B, in which is placed a half-circular or semi-tubular steel plate, C; provided at each end at both upper edges with projecting lugs *a a*, which embrace the ears of the shackle, as shown. Through the bottom of the shackle, in the center, is passed a set-screw,

D, which enters the same, and is swiveled thereto.

E represents the thill-iron, having a cylindrical eye, G, formed on its end. This eye is inserted in the shackle within the semi-tubular plate C, and is held by a bolt, b, as shown, and a nut, d, on the end thereof. By now screwing up the bolt or set-screw D the plate C is held up tight against the eye G, preventing all noise and rattling.

This thill-coupling is simple and cheap in construction, dispensing with all springs and rubbers, and it is not liable to get out of order.

What I claim as new, and desire to secure by Letters Patent, is—

The semi-cylinder C, having the projecting lugs *a*, screw-threaded perforation *m*, and set-screw D, swiveled to said semi-cylinder, in combination with the shackle B, thill-iron eye G, and bolt *b*, substantially as described, and for the purpose set forth.

In testimony that I claim the above I have hereunto subscribed my name in the presence of two witnesses.

HUGH DICK.

Witnesses:

C. SIMMONS,
PETER BELLINGER.
